UNITED STATES PATENT OFFICE.

BENJAMIN LILLARD, OF NEW YORK, N. Y.

DESIGN FOR SHEARS.

Specification forming part of Design No. **11,279**, dated July 1, 1879; application filed May 16, 1879.
[Term of patent 14 years.]

To all whom it may concern:

Be it known that I, BENJAMIN LILLARD, of the city, county, and State of New York, have invented a new Design for Office-Shears, of which the following is a specification.

Figure 1 is a side view of an office-shears illustrating my design, showing in full lines the shears closed, and in dotted lines the shears opened. Fig. 2 is a cross-section taken through the line *x x*, Fig. 1.

Similar letters of reference indicate corresponding parts.

A and B are the handles, and C and D are the blades, of office-shears. The blades C and D are rounded or beveled upon their outer

sides and upon the outer part of their inner sides to give them when closed the form of a paper-knife, as shown in Fig. 2.

Having thus fully described my invention, I claim as new and desire to secure by Letters Patent—

A design for shears, in which the blades C D are rounded or beveled upon the outer sides and upon the outer parts of their inner sides, substantially in the manner herein shown and described.

BENJAMIN LILLARD.
